CLARENCE D. VEST, OF SAN FRANCISCO, CALIFORNIA, ASSIGNOR TO A. B. SMITH, OF SAN FRANCISCO, CALIFORNIA.

DISPLAY BOX.

Application filed January 31, 1927. Serial No. 164,905.

This invention relates to improvements in display boxes.

The principal object of this invention is to produce a box which will display the goods contained therein, and at the same time provide means for excluding moisture from entering said box.

Another object is to produce a box wherein the contents thereof may be seen and withdrawn when desired, and at the same time provides means for re-sealing the box so as to protect any contents which may be left in the box.

A further object is to produce a box where-in it will be easy to assemble and economical to manufacture.

A still further object is to produce a box wherein one portion of the contents may be maintained in a sealed condition, while the other portion of the box is being emptied.

Other objects and advantages will be apparent during the course of the following description.

In the accompanying drawings forming a part of this specification and in which like numerals are employed to designate like parts throughout the same,

Figure 1 is a perspective view of my box with the inner container partly removed from the outer container.

Figure 2 is a top plan view of the blank out of which my box is constructed,

Figure 3 is a perspective view showing my box in the first stage of assembly,

Figure 4 is a cross-sectional view of my box as it would appear when ready to be filled,

Figure 5 is an enlarged detail cross-section of my box, an outer container on an enlarged scale, and

Figure 6 is a modified form of my box.

In the packing of certain commodities, such as breakfast food, dried fruits and the like, it is essential that the same be protected against the entrance of moisture as long as the contents remain within the package. It is also a great advantage to be able to observe the contents of the box, as the pleasing appearance often results in sales.

I have therefore devised a box which will not only maintain the commodities placed therein, in a dry condition, but I have further provided means whereby the contents of the box may be withdrawn as a whole or gradually in such a manner that the box may be

readily resealed. If desired, I have further provided means whereby the contents of the box may be observed in such a manner that the box when placed upon a store shelf will occupy substantially the amount of space twice that ordinarily required by a box of the same size. In other words the inner box is removed from its cover and the cover and inner box positioned side by side gives the appearance of two boxes. This is an advantage to a small grocer who does not care to carry a large stock. The result being that a few boxes gives the appearance of a large supply.

In the accompanying drawings wherein for the purpose of illustration is shown a preferred embodiment of my invention, the numeral 5 designates an outer container, and the numeral 6 an inner container. The outer container is provided with depressions 7 and 8, while the inner container is provided with circular openings 9 and 11.

Referring now to Figure 2, it will be noted that the blank consists of a bottom portion 12, side portions 13 and 14, a top portion 16 and auxiliary side portion 17, and an auxiliary top portion 18. The top portion 16 and the auxiliary top portion 18 are each provided with a window, as shown at 19 and 21 respectively. The bottom portion has formed integral therewith, ends 22 and 23, while the side portions 13 and 14 have flaps 24-25 and 26-27 respectively. The auxiliary top portion 18 is likewise provided with end pieces 28 and 29. The auxiliary side portion 17 has openings 31 and 32 which are so positioned as to coincide with the openings 9 and 11 when the box is in folded position.

In assembling my box, the various portions are folded upon the dotted lines of Figure 2, so as to first bring the parts to the position shown in Figure 3, at which time a sheet of transparent material 34 is inserted between the side 14 and the auxiliary side 17.

By now referring to Figure 4, it will be noted that the edges of the openings, as for instance, the openings 11 and 32, are each formed with an outstanding rim, the result being that the transparent material 34 is caused to assume intimate contact at all points adjacent these openings, thereby effecting a seal at this point. After the box has been filled, the transparent material is folded over together with the auxiliary top 18, after

which this top and its ends 28 and 29 are glued or otherwise secured to the contacting portions of the box. This results in the transparent material being securely held between the top 16 and the auxiliary top 18, therefore the goods contained within the receptacle may be readily observed, while they are amply protected against the entrance of any moisture.

- 10 In order to protect the box during shipment or while on display, I have provided an outer container into which the box proper may be slid. This outer container has depressions 7 and 8 formed therein, which depressions coincide with the openings 9 and 11 of the box, the result being that these depressions further seal the openings 9 and 11, as indicated in Figure 4. This sealing feature permits the transparent material 34 being punctured at a point where it covers the openings 9 and 11, so that the contents of the box thereof, may be emptied therethrough, after which when the outer container is replaced, the openings are sealed.
- 15
- 20
- 25 It will thus be seen that I have produced a box which is moisture proof when on display, and is further moisture proof when in use and the contents are being withdrawn therefrom. In the modified form shown in
- 30 Figure 5 I have inserted a partition 36, which divides the box into two compartments. When this type of box is employed, first one

compartment is emptied, after which the other compartment is emptied.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

A display box of the character described, comprising a blank so folded as to form a bottom, sides and ends of a box, a top formed integral with said blank, said top having a window formed therein, an auxiliary side formed integral with said blank, said auxiliary side having openings and adapted to coincide with similar openings formed in one of said first mentioned sides, a transparent material interposed between said auxiliary side and in said butting side portion, said transparent material being folded over and upon said top portion, an auxiliary top portion formed integral with said blank and adapted to be folded upon said top portion in such a manner as to overlie said transparent material.

In testimony whereof I affix my signature.

CLARENCE D. VEST.
